ABSTRACT: In a pushbutton control device having a plurality of actuator members movable between first and second positions within a support housing for operating associated switches or the like, each actuator is biased towards its first position and is provided with an associated detent member for retaining its respective actuator in its second position, and the individual detent members are interconnected by a force transmitting mechanism which is adapted to release the detent member of an actuator in its second position to permit return of that actuator to its first position in response to movement of any other actuators to its second position.

SHEET 4 OF 4

FIG. 11.

PUSHBUTTON DEVICE

This invention relates generally to pushbutton control devices, and more particularly to control devices having a plurality of pushbutton control members movable between two operative positions and interconnected such that as any one of the control members is moved to one of its operative positions, a control member previously in that operative position is returned to its other operative position.

Pushbutton control devices of the above type have previously been proposed which utilize a relatively complex arrangement of spring-mounted elongated plates or levers for interconnecting the control members. While these devices have proved satisfactory for certain applications, they are subject to numerous restrictions which limit their usefulness. In particular, these devices are limited to applications wherein the control members are in longitudinal alignment since the operating levers can only function as required if they are straight members. Moreover, the number of control members which can be operatively associated with each other in the control device is limited.

Accordingly, it is an object of the present invention to increase the number of control members capable of operation in pushbutton control devices of the described type, and more particularly to increase this number and yet provide a device wherein the control members are slidably operable with a relatively soft manual touch.

Another object of the invention is to permit locating the control members in pushbutton devices of the described type in a variety of relative positions and arrays.

It is a further object of the present invention to provide a relatively inexpensive and simply constructed pushbutton control device which is readily operated by a soft manual touch.

In accordance with an aspect of this invention, a pushbutton control device is provided with a supporting housing containing a plurality of actuators mounted therein for movement between a first position and a second position in which, for example, the actuators are adapted to close the contacts of an associated switch or the like. Each of the actuators is biased towards its first position, for example, by spring loading of the associated switch, and has a recessed surface portion within the support housing. An individual ball detent is associated with each of the actuators to hold the latter in its second position, and the several ball detents are operatively interconnected by differential-force-applying means, which urges each of the detents against its associated actuator. In one embodiment this force-applying means comprises generally trapezoidally shaped members positioned between the detents and between the latter and a pair of end bearing blocks, and the bearing blocks compact the trapezoidal members and the detents and thereby urge the detents against their actuators. As any individual actuator is moved to its second position, its associated detent is moved into the recessed portion thereof and the force applied by the trapezoidal members to the detent associated with an actuator previously moved to its second position is reduced, so that the previously moved actuator is returned to its first position.

The construction of a pushbutton control device in this manner and in accordance with this invention eliminates the levers and springs of prior devices which limited the size and configuration of such devices. Moreover, the present invention permits the construction of such devices in numerous configurations and sizes and as more fully described hereinafter permits the use of individual sectional support members which may be interconnected to vary the size and arrangement of the device in accordance with specific requirements.

The above, and other objects, features and advantages of this invention, will be apparent in the following detailed description of illustrative embodiments of this invention which is to be read in connection with the accompanying drawings wherein:

FIG. 1 is a longitudinal sectional view of a pushbutton control device according to an embodiment of the present invention, as viewed along the line I—I of FIG. 3;

FIG. 2 is a sectional view taken on line II—II of FIG. 1;

FIG. 3 is a sectional view taken on line III—III of FIG. 1, and showing a control member in its first position;

FIG. 4 is a sectional view similar to FIG. 3, but illustrating a control member in its second position, and which is taken on line IV—IV of FIG. 1;

FIG. 5 is a sectional view similar to FIG. 1, but showing another embodiment of the present invention;

FIG. 6 is a plan view of a further embodiment of the present invention wherein the control members are located in a circular array;

FIG. 7 is a sectional view taken on line VII—VII of FIG. 6;

FIG. 8 is a fragmentary sectional view taken on line VIII—VIII of FIG. 7;

FIG. 9 is a view similar to FIG. 1, but showing still another embodiment of the present invention;

FIG. 10 is a sectional view taken on line X—X of FIG. 9;

FIG. 11 is a top plan view, partly broken away and in section, of another embodiment of the present invention;

FIG. 12 is a side elevational view, partly in section, taken on line XII—XII of FIG. 11;

FIG. 13 is a perspective view of a connecting-spring member utilized in the embodiment of the invention illustrated in FIGS. 11 and 12;

FIG. 14 is a view similar to that of FIG. 4, but showing still another embodiment of the present invention with the actuator member being in its second position; and

FIG. 15 is a view similar to that of FIG. 14, but in which the actuator member is in its first position.

Referring to the drawings in detail, and initially to FIGS. 1 and 2 thereof, it will be seen that the pushbutton control device embodying the present invention, as there shown, comprises a support member or housing 10 formed by frame members 12 and 13 which receive actuators 14 for operating respective switches 15. The frame members 12 and 13 are preferably formed of a plastic which, while being substantially rigid, has some resiliency.

For convenience in describing the invention, each of the actuators 14 and the various elements associated therewith are indicated with subscripts *a*—*e*, and while only five such actuators are shown in the drawings and described, it is contemplated that any number of actuators may be provided in a pushbutton control device incorporating the present invention

in accordance with the requirements of the particular application involved.

Frame member 12 is formed with a plurality of individual chambers 16 each of which is adapted to slidably receive one of the actuators 14 for sliding movement therein between a first position (FIG. 3) occupied by actuators 14*a*, *b*, *d* and *e* as seen in FIG. 2, and a second position (FIG. 4) occupied by actuator 14*c* in FIG. 2. The ends 18 of the actuators contact the control members 20 of switches 15, and such control members 20 are biased upwardly by spring means (not shown) to urge actuators 14 towards their first position which, for example, may correspond to the open contact condition of the associated switches. In its second position, each of the actuators, e.g., actuator 14*c*, depresses control members 20, for example, to close the contacts of its associated switch 15*c*.

While actuators 14 are normally maintained in their first position under the influence of control member 20, when any one of the actuators, for example, actuator 14*c*, is moved to its second position, it is held there against the bias of member 20 by an actuator control system 22 contained in a longitudinally extending chamber 24 formed in frame member 12. As seen in FIG. 1, chambers 16 open into chamber 24 and actuator control system 22 operatively interconnects the actuators 14, so that, as more fully explained hereinafter, as one actuator, 14*d* for example, is moved to its second position, any actuator, 14*c* for example, previously in its second position, is allowed to return to its first position under the urging of its associated spring biased control member 20.

Each actuator 14 is formed with an enlarged central portion or block 26 slidably received in the respective chambers 16 and having a cam or detent surface 28 (FIGS. 3 and 4) which is

adapted to cooperate with a ball detent member 30 of actuator control system 22 during operation of the device. Ball 30 is urged into contact with cam surface 28 by a differential force applying mechanism forming part of control system 22 and which, in the embodiment of FIGS. 1 and 2, includes generally trapezoidally shaped slide members 32 positioned for longitudinal movement between adjacent ball detents 30. Members 32 have inclined surfaces 34 which engage balls 30 at points 35 on their surfaces lying in intersecting tangentially extending planes which form an angle therebetween opening towards actuators 14. Balls 30 and members 32 are compacted or urged into contact with each other by bearing blocks 38 contained within the end portions of chamber 24 adjacent the endmost ball detents 30a and 30e.

Bearing blocks 38 have inclined surfaces 40, corresponding to surfaces 34, engaging balls 30a and 30e at corresponding points 35 and are displaced towards each other by setscrews 42 threadably engaged in frame 12. Thus, the longitudinal resilience of frame members 12 and 13 longitudinally compacts system 22. In this manner, a pair of angularly related forces, indicated by the arrows 41 on FIG. 1, are applied to each ball 30 at points 35 and these forces combine in a resultant force 43 which urges ball 30 into contact with surface 28 of the associated actuator 14.

Cam surface 28 includes a recessed portion 28a, a central cam portion or shoulder 28b, and a land portion 28c (FIGS. 3 and 4) against which resultant force 43 urges ball 30 during operation of the device. As seen in FIG. 3, when any actuator, for example actuator 14e, is in its first position, its associated ball detent 30e is urged by surfaces 34 into contact with land portion 28c of actuator 14e (FIG. 3) and the actuator is held in its first position, for example, wherein the contacts of switch 15 are open, by the spring-biased control member 20. On the other hand, when an actuator member, for example, actuator 14c, is moved to its second position (FIG. 4), force 43 urges ball 30c into recess 28a wherein it engages cam portion or shoulder 28b and holds actuator 14c in its second position against the upward bias of switch member 20.

Referring again to FIG. 1, it will be seen that the relative movements of the elements within actuator control system 22 are there illustrated during movement of one actuator 12d from its first position to its second position. Initially, the elements are positioned, as shown in solid lines in FIG. 1, with actuator 14d in its first position and another actuator, for example, actuator 14c, in its second position, wherein ball 30d engages surface 28c of actuator 14d and ball 30c engages surface 28a of actuator 14c. When the upper pushbutton portion of actuator 14d is engaged and depressed, to move that actuator to its second position against the bias of its associated switch, the recessed portion 28a thereof is moved to a position opposite ball 30d which in turn, is moved (as shown in dotted lines in the drawing) by resultant force 43 into engagement therewith. As ball 30d moves into recess 28a it tends to move away from slide 32c, however, slide 32c is kept in contact with ball 30d and is moved laterally to the right, that is towards ball 30d, at a substantially right angle to the resultant force 43, under the influence of the biasing forces applied by setscrews 42 and the switch control member 20 associated with previously depressed actuator 14c which urges the cam surface or shoulder 28b of actuator 14c upwardly to move ball 30c out of its associated recessed portion and against slide members 32b and 32c. As slide member 32c is moved to the right, the angularly related forces 41 applied to ball 30c are reduced, and the upward biasing force of switch 15 and control member 20 moves actuator 30c upwardly against the reduced resultant force 43 to return actuator 14c to its first position.

The principles of operation of the device are the same for any combination of actuators, and for example, if actuator 12a were in its second position and actuator 12e were being moved from its first position to its second position, all of the intermediate members, i.e. 32a, b, c, d and balls 30b, c, d would move to the right, as seen in FIG. 1, to compensate for the movement of ball detent 30e and to release ball detent 30a for return of actuator 14a to its first position.

It is thus seen that as any one actuator member is moved from its first to its second position, for example, to close the contacts of its associated switch, any actuator previously occupying its second position is automatically returned to its first position, for example, to open the contacts of its associated switch. By this arrangement it should be evident that any number of actuator members may be provided in housing 10 since all of the elements in actuator control system 22 are operatively interconnected for direct transmittal of forces therebetween, and therefore, the force required for operating any one of the actuators will be substantially the same for any number of actuators.

FIG. 5 illustrates another embodiment of the present invention, and elements of this embodiment, and in the other hereinafter described embodiments, which correspond to elements described above with respect to the embodiment of FIG. 1, are designated by like numerals and subscripts. As seen in FIG. 5, the pushbutton control device 50 there illustrated comprises a pair of frame or housing members 52 and 54 which slidably receive actuator members 14a-14e within chambers 56 and formed in frame member 52. In lieu of the trapezoidal slide members 32 of the prior embodiment, pushbutton control device 50 is provided with a plurality of balls 55 positioned between the detent balls 30 associated with each of the actuators 14. Frame members 52 and 54 cooperate to provide an elongated chamber 56 having offset chamber portions 58 located between actuators 14 and in which balls 55 are accommodated. By this construction the centers of balls 30 are closer to their associated actuators 14 than are the centers of balls 55, and thus balls 55 engage the surface of ball members 30 at points 35 which lie on intersecting tangentially extending planes defining an angle opening towards actuators 14.

Bearing blocks 38 are again provided adjacent endmost detent members 30a and 30e and are urged towards each other by setscrews 42 so that detents 30 are held in contact with balls 55. In this manner the angularly related forces 41 are applied to ball detents 30 and as before, these forces combine to form the resultant force 43 which urges ball detents 30 into engagement with their associated actuator members. Ball members 55 are free to slide within intermediate chamber sections 58 and thus, as any one of the actuator members 14 is moved to its second position, the balls 55 in the chamber may move longitudinally in the manner described above with reference to trapezoidal members 32.

The use of ball members 55 in lieu of trapezoidal members 32 reduces the amount of friction present within the device since balls 55 have minimal contact with chambers 58. Further, it is evident that only a single ball 55 or more than two balls may be used within a housing 50 having appropriately dimensioned intermediate chambers 58. The complete operation and function of the device is substantially the same as that described above with respect to the embodiment of FIG. 1 and therefore further detailed description thereof is not considered necessary.

FIG. 6 illustrates a pushbutton control device according to another embodiment of the present invention in which the actuators 14 are disposed in a circular array in a generally circular-shaped housing 60. Housing 60 includes annular, concentric frame members 62 and 64 which are also preferably formed of a substantially rigid, somewhat resilient plastic material. Member 62 corresponds to frame member 12 of the embodiment of the invention illustrated in FIG. 1 and defines an annular chamber 66 which is adapted to receive the actuator control system 22 (FIG. 8). In addition, frame member 62 provides a plurality of chambers 68 arranged in a generally circular pattern and receiving the enlarged central portions 26 of actuators 14. Frame member 64 closes the inner side of chamber 66 and retains trapezoidal members 32 and detent balls 30 of actuator control system 22 within that chamber. The detent balls 30 are, as in the prior embodiments, urged towards the surfaces 28 of actuators 14 by resultant forces 43 formed from the angularly related forces 41 applied to the detent balls by the trapezoidal members 32. The dimensions of

the trapezoidal members 32 and ball detents 30 are selected so that, when such elements are disposed within annular chamber 66 and engaged with frame members 62 and 64, they are pressed against each other by the resilience of the frame members to provide the biasing forces supplied in the previous embodiments by setscrews 42 and bearing blocks 38. The biasing forces 41 and resultant forces 43 thus created are sufficient to retain an individual actuator member in its second or depressed position.

In FIG. 7, the actuator 14d is illustrated in its second position, and the associated detent ball member 30d is shown engaged with recessed portion 28a. In this embodiment, as shown, the switches are each constituted by a pair of resilient contact strips 70 and 72, which are mounted respectively on frame members 62 and 64 so as to be spaced from each other so long as the respective actuator 14 is in its raised first position. Strips 70 bias actuators 14 towards their first positions in which the switch contacts provided by strips 70 and 72 are open, as seen in FIG. 7 with respect to actuator 14d. When an individual actuator member, for example the actuator 14d, is depressed to its second position, its base portion 18 moves against the associated strip 70d to engage the latter with contact strips 72d, and the associated ball detent 30d moves into recessed surface portion 28a to hold actuator 14d in its second position against the bias of lever 70d. As illustrated in FIG. 8, when an actuator, for example actuator 14e, is moved to its second position, resultant force 43 applied to the detent member of a previously depressed actuator, for example, actuator 14d, is relieved so that actuator 14d is free to be returned to its first position by the associated resilient contact strip 70d in substantially the same manner as the actuators of the prior embodiments.

The pushbutton actuator device of FIGS. 6-8 is particularly adapted for use as a television channel selector, and the sets of resilient contact strips 70 and 72 constituting switches may be employed to select or tune for respective channels and also to suitably energize a number display tube 74 contained within the generally cylindrical space 76 defined by frame member 64. Display tube 74 is mounted in frame 64 by an annular insulation member 78 and operates in a well-known conventional manner so that when an individual actuator member is depressed, for example actuator 14d, and its end portion 18 closes the contacts between strips 70d and 72d, the display device 74 is energized and produces the image of the number 4. This image is displayed through a window 75 in the housing cover plate 77 for observation by a viewer. When another actuator member is depressed, for example actuator 14e, the contact between strips 70d and 72d associated with actuator 14d is broken and the numeral 4 fades from the display device; and, at the same time, contact strips 70e and 72e associated with actuator 14e are engaged to change the selected channel and to display the corresponding numeral, for example, the numeral 5.

As mentioned, the structure of the present invention is adapted to be embodied in a variety of actuator arrangements and permits a wide choice in the number of actuators provided in an individual control unit. In FIGS. 9 and 10, there is illustrated a pushbutton control device 80 in accordance with the present invention in which each of the actuator members 14 is contained in an individual housing 82, each of which is adapted to be interconnected to another housing to vary the number of actuators in the completed unit.

For illustrative purposes, three housing, 82a, b and c are shown in the drawings, however, it is clear that any number of such housings may be provided in accordance with the particular application in which the control device is to be used. Each of the housings 82 is formed with a chamber 84 which is adapted to slidably receive an actuator member 14, constructed in the same manner as the actuators of the prior embodiments. In addition, each of the housings includes a second chamber 86 which corresponds to chamber 24 of the embodiment in FIG. 1 and which contains an actuator control system 88 constructed in accordance with the present invention. This

system includes a pair of slide members 90 having opposed inclined surfaces 92 adapted to contact a ball detent member 30 at points 35 to apply the angularly related forces 41 to the ball for urging it into engagement with the recessed surface portion 28a of its associated actuator member 14.

Each of the housings 82 further includes a first end portion 96 having a threaded exterior surface and a second opposed end portion 98 having a complementary thread form on its interior surface, whereby the housings are adapted to be connected in longitudinal alignment, as illustrated in FIG. 9. The slide members 90 within each of the housings extend into end portions 96 and 98 and, when the housings are threadably interconnected, the end surfaces 100 of slide members 90 are in direct contact, and effectively form a single trapezoidal member between adjacent ball detents 30 which corresponds to a member 32 of the embodiment illustrated in FIG. 1.

The end portion 96a of endmost housing 82a is threadably engaged by a cap 102 having a stem portion 104 which abuts against the adjacent slide member 90 to retain the slide within housing 82a. The end portion 98c of endmost housing 82c, of the completed pushbutton device shown in FIG. 9, threadably receives a plug 106 having a setscrew 108 which engages the adjacent endmost slide member 90 within housing 82c. Setscrew 108 is threaded into plug 106 to contact endmost slide 90 and in cooperation with cap 102 impresses a biasing force on the slides 90 to urge the slides into engagement with their associated ball detent members 30 whereby the balls 30 are urged into contact with their associated actuators in substantially the same manner as the detent members of the prior embodiments.

As shown on FIG. 10, the spring bias of each of the switches 15 may not be relied upon for returning the respective actuators 14 to their first positions. In that event, a compression-spring member 110 is provided about the upper portion 112 of each of the actuators to bias the actuator towards its first position. Spring 110 engages the top portion 114 of each of the housings 82 at one end and at its other end engages the lower portion of pushbutton 116 formed at the top of the actuator. In this manner each of the actuators is urged to its first position and the device is adapted to operate and function in substantially the same manner as that described for the prior embodiments, but with the control member 20 of each switch 15 merely following the movements of the actuator 14.

FIGS. 11 and 12 illustrate a pushbutton control device 120 according to another embodiment of the present invention wherein actuators 14 are mounted in individual housings 121 for operative interconnection with other like housings in order to vary the size and configuration of the pushbutton control device. In this embodiment, each of the housings 121 is provided with a chamber 122 slidably receiving an individual actuator 14 and a second chamber 124 adapted to receive the actuator control mechanism 126. Control mechanism 126 includes a ball detent 30 adapted to engage the surface 28 of its associated actuator 14 to retain the actuator in its second position as in the prior embodiments. In addition, mechanism 126 includes a pair of slide members 128 which correspond to slide members 90 of the embodiment of FIGS. 9 and 10 and which include inclined surfaces 130 serving to urge balls 30 into engagement with their associated actuators.

However, the outer ends of the members 128 have curved surfaces 132 which extend into end portions of the housings 121 and are adapted to engage the corresponding surfaces 132 of the slide members 128 contained within adjoining housings 121 when the housings are interconnected in the manner hereinafter described. It is noted that slide members 128 each include a stepped-down portion 129 adjacent curved surface 132 to define a shoulder 131 on the slide which cooperates with a shoulder 133 formed in chambers 124 to retain the slide within the respective housing.

Housings 121 are each provided with opposed pairs of arms 136 and 138 which serve to pivotally interconnect adjacent housings 121 so that curved surfaces 132 of adjacent slides 128 are placed in direct contact with each other for force

transmittal therebetween. Arms 136 include generally downwardly extending projections 140 which are received within similar generally circular recessed portions 142 formed in the offset arms 138 of an adjacent housing. The pivotal connections thus provided permit the housings to be disposed in any required positions with respect to each other. The end-most slide member 128 in housing 121a is engaged by a stop member 144 fixed to housing 121a to abut and retain the slide member. The opposed end of the group of interconnected housings 121a, b and c, illustrated in FIG. 11 is provided with a cap 146 fixed to the housing 121c in any conventional manner. This cap threadably receives a setscrew 148 which engages endmost slide member 128 contained within housing 121c in order to urge slide members 128 into contact with their associated ball detents 30 and thereby urge the balls into contact with the associated actuators 14.

In this embodiment, actuators 14 are provided with spring members 110 surrounding their stem portions 112 to urge the actuators to their first positions. These spring members serve to supplement or to replace the upward biasing action of the group contained in switches 15 of prior embodiments.

To insure maintenance of the pivotal connection between housings 121, a generally U-shaped spring member 150 (FIG. 13) may be provided to hold arms 136 and 138 in mutual engagement. Each such member 150 is shown to include a pair of projections 152, which are adapted to be received in recesses 154 formed in arms 136 and 138 of adjacent housings. Referring to FIG. 12 it is seen that arms 136 and 138 are positioned such that an arm 138 of housing 121b is immediately above arm 136 of housing 121c. Spring member 150, having its projections 152 received in the recesses 154 formed in each of these arms urges the arms apart, and into engagement with the other arms 136 and 138 of housings 121, to maintain engagement therebetween.

FIGS. 14 and 15, which are similar to FIGS. 3 and 4, but illustrate another embodiment of the present invention for use where the control function to be performed may require both a linear displacement of the actuator and a rotational movement thereof. In this embodiment, housing 160 may be similar in construction to the housing 10 of the embodiment in FIG. 1 and contains an actuator control system 22 constructed in accordance with that embodiment. In lieu of actuators 14, however, cylindrically shaped actuators 168 are provided which include a slide member 166 contained within chamber 18 and have a cylindrically recessed surface portion 166a, an annular cam-shaped portion or shoulder 166b and a cylindrical land portion 166c. By their generally cylindrical construction, actuators 166 are rotatable within chambers 18 and are each adapted to engage the spring-biased control member 20 of the associated switch 15 in the same manner as the actuators 14 employed in the embodiment of FIG. 1. However, the end portion 168 of each actuator 162 is also provided with a gear member 170 which is adapted to mesh with a larger gear member 172 when the actuator is in its second position, as seen in FIG. 14. Gear 172 may be connected to a variable value element, as for example, a variable resistor or capacitor, and therefore, when an actuator 162 is in its second position it may be rotated to vary the value of element 174. This arrangement is particularly adapted for use with pushbutton channel selectors for television or radio sets, since generally speaking it is desirable to have preset tuning for this type of equipment. Accordingly, when one of the actuators 162 is moved to its second position it may be rotated to vary the value of the associated condenser or resistor 174 to preset the tuning thereof. Once this adjustment is made the device need not be readjusted since the tuning of each of elements 174 is set and will remain at the preset value until changed. The basic operation of the pushbutton device of FIGS. 14 and 15 is the same as that of the embodiment described above with respect to FIG. 1 with the additional preset tuning refinement and accordingly further detailed description thereof is considered unnecessary.

While each of the above embodiments of the present invention has been described as being adapted to operate electrical switches, particularly in television or radio sets, it is apparent that pushbutton control devices in accordance with the present invention may equally be adapted for use to control mechanical switches or valves, for regulating fluid flows. Further, although illustrative embodiments of the present invention have been described herein with reference to the accompanying drawings, it is to be understood that the invention is not limited to those precise embodiments, and that various changes and modifications may be effected therein by one skilled in the art without departing from the scope or spirit of this invention.

What is claimed is:

15. 1. A pushbutton device for operating switches or the like, comprising support means, a plurality of pushbutton members having actuators extending therefrom and being mounted in said support means for movement relative thereto between first and second positions, means biasing said actuators towards said first position, individual detent means associated with each of said actuators and being movable to an operative position when the respective actuator is moved to said second position to hold said respective actuator in said second position, and differential force-transmitting means interconnecting said individual detent means associated with said actuators and applying a biasing force to each of said detent means to urge said detent means toward said operative position, said force applying means reducing the biasing force applied to the detent means of an actuator which has been previously moved to said second position and thereby permitting its return to said first position in response to the movement of any other one of said actuators to said second position thereof.
2. A control mechanism for switching units or the like, comprising support means, a plurality of pushbutton control members extending from said support means and being movable between first and second operative positions, said members each having a recessed surface portion within said support means, means urging said control members towards said first operative position, individual detent means in said support means associated with each of said control members and engaging the respective recessed surface portion when the associated control member is moved to its second operative position for holding said associated control member in said second position, differential force-applying means interconnecting said detent means and applying a biasing force to each of said detent means to urge said detent means against their associated control members, said force-applying means reducing the biasing force applied to the detent means associated with a control member previously moved to its second position, thereby to release said control member for return to its first position, in response to the movement of any other one of said control members to said second position thereof.
3. A control mechanism as defined in claim 2, wherein said control members are aligned in spaced relation within said support means, said force-applying means comprises means slidably mounted in said support means between adjacent detent means for interconnecting said adjacent detent means and for applying said biasing force thereto, whereby the interconnecting means between a control member previously in its second position and any other control member are adapted to slide along a line generally perpendicular to said biasing force and towards said other control member as said other control member is moved to its second position, to maintain contact with each of said detent means as said detents are moved into and out of engagement with said recessed actuator surface portions.
4. A control mechanism as defined in claim 3, wherein said detent means comprises ball detents and said interconnecting means comprises means for engaging said ball detents at two points on the spherical surfaces thereof lying on intersecting tangentially extending planes which enclose an angle opening towards said actuator, whereby a pair of angularly related forces are applied to each of said balls which combine to pro-

vide said biasing force urging said ball detents against their associated control members.

5. A control mechanism as defined in claim 4, wherein said force-applying means includes bearing blocks slidably mounted in said support means adjacent the endmost ball detent members and means cooperating with said support means for urging said bearing blocks towards each other and against said endmost ball detents whereby each of said detent balls is forced into contact with said engaging means to produce said angularly related forces.

6. A control mechanism as defined in claim 4, wherein said interconnecting means comprises a plurality of generally trapezoidally shaped members, each of said members being positioned between an adjacent pair of individual detent means and having oppositely inclined surfaces lying in said intersecting tangential planes and adapted to contact said ball detents for applying said angularly related forces thereto.

7. A control mechanism as defined in claim 4, wherein said interconnecting means includes at least one force-transmitting ball positioned between said adjacent ball detents, each of said force-transmitting balls being offset from said ball detents whereby they are adapted to engage said detents at said two points and apply said angularly related forces thereto.

8. A control mechanism as defined in claim 3, wherein said control members are aligned in a generally circular array in said support members.

9. A control mechanism as defined in claim 3, wherein said support means comprises a plurality of individual support sections each of said support sections containing at least one of said control members and means for operably interconnecting said support sections to form an integral pushbutton control mechanism.

10. A control mechanism as defined in claim 3, wherein said support means comprises a plurality of pivotally interconnected support sections, each of said sections being adapted to contain at least one of said control members.

11. A control mechanism as defined in claim 3, wherein said control members are generally cylindrically shaped members adapted to be rotated within said housings.

12. A control mechanism for switching units or the like, comprising a plurality of elongated pushbutton control members each including a recessed surface portion and being adapted to be alternately moved between first and second operative positions, support means movably receiving the recessed portions of said control members and adapted to 10 contain said control members between said first and second positions, means for biasing said control members towards their first position, a ball detent slidably contained in said support means adjacent each of said control members and adapted to engage the respective recessed portion thereof 15 when the associated control member is moved to said second position, a plurality of trapezoidally shaped detent biasing members slidable within said support means, each of said biasing members being positioned between an adjacent pair of ball detents, said biasing members having their nonparallel sides 20 contacting said adjacent ball detents and defining an angle therebetween opening towards their respective control members, means urging said detent-biasing members towards each other to apply a biasing force to each of said detents at their points of contact with said nonparallel sides, said forces 25 combining to provide a resultant force urging said ball detents against their associated control members, whereby, as one of said control members is moved from its first to its second position its associated ball detent is moved into the respective recessed portion thereof by said resultant force to hold said 30 one control member in said second position against the action of said biasing means, the biasing forces applied to the remainder of said detents being decreased by said ball detent movement to allow any control member previously in said first position to be returned to its second position by said biasing 35 means.
